Primary Examiner—Brian N. Vinson*Attorney, Agent, or Firm*—Harold H. Dutton, Jr.[57] **CLAIM**

The design for a portable, hand held fertilizer dispenser, as shown and described.

DESCRIPTION

FIG. 1 is a rear elevational view of a portable, hand held fertilizer dispenser showing our new design;

FIG. 2 is a front elevational view thereof;

FIG. 3 is a right side elevational view thereof, the left side being a mirror image of that shown;

FIG. 4 is a top plan view thereof; and,

FIG. 5 is a bottom view thereof.

*FIG. 1**FIG. 2**FIG. 4**FIG. 3**FIG. 5*
